UNITED STATES PATENT OFFICE.

EMANUEL W. DUNN, OF SAN FRANCISCO, CALIFORNIA.

WEATHER.

1,144,699.

Specification of Letters Patent. Patented June 29, 1915.

Application filed September 9, 1912. Serial No. 718,291.

To all whom it may concern:

Be it known that I, EMANUEL W. DUNN, a citizen of the United States, residing at San Francisco, in the county of San Francisco, State of California, have invented new and useful Improvements in Heaters, of which the following is a specification.

This invention relates to open air heaters particularly adapted for heating a locality or zone to prevent damage of fruit and the like by frost and freezing; although the invention is capable of other uses without material change. And, more particularly, this invention relates to a heater of the class described containing its own fuel reservoir for holding a sufficient supply of liquid fuel for a suitable period of operation.

It is one of the prime objects of my present invention to supply, in such a heater as set forth, a simple and efficient air feed which is capable of supplying the liquid fuel with all the air necessary for complete and thorough combustion at any desired rate, and in such manner as to cause the complete combustion of all of the fuel. By efficiently supplying air for combustion I provide that there shall be no liquid matter left unconsumed, either exterior to or interior of the heater. It has been shown to be of great advantage to provide for perfect and sufficient combustion in order to prevent the deposition of oily soot and similar solid carbon and oil particles on the fruit which is being protected; and it also works greatly for efficiency to consume these elements of fuel combustion, the combustion thereof adding greatly to the heat of the flame and to the heat deliverable to the surrounding locality.

There are two features which I wish to particularly emphasize in the following specification, both relating to my peculiar and novel construction of combustion outlet and flue. These features have as their object the handling of combustible gases and the provision of auxiliary air so that the gases may be efficiently consumed.

With a heater as above outlined I am enabled to deliver a large volume of heat units which spread over the surrounding locality, heating the atmosphere therein and preventing the deposit of frost by primarily preventing the lowering of temperature in the affected zone. The heated gases of combustion carry very little or no solid matter

which will deposit on the fruit and on other adjacent objects.

I will now proceed to a detailed explanation of my improved heater, reference being had to the accompanying drawings, in which,

Figure 1 is a vertical section of one form of my improved heater, Fig. 2 is a plan view of the upper end of the combustion flue thereof, showing the damper control therefor, Fig. 3 is a plan view taken as indicated by line 3—3 of Fig. 1, Fig. 4 is a detail view showing a form of controlling means for the inwardly flowing air, Fig. 5 is a detail section showing another form of air controlling means, Fig. 6 is a section similar to that of Fig. 1, showing a modified means of air control, Fig. 7 is a perspective of the form shown in Fig. 6.

Referring now particularly to the drawings, I will say that my device includes essentially a liquid fuel receptacle or reservoir 20, a combustion outlet indicated generally by the numeral 21 and air inlet or inlets indicated generally by the numerals 22. In each of the forms shown in the drawings it will be noted that the air inlets are of such arrangement and design that the inward flow of air is formed into a downward blast or current which delivers over the surface of the liquid fuel within the reservoir. This is in general my preferred mode of operation, although I may and do use means other than those specifically illustrated to accomplish the desired end. I may use a simple opening in the top of the reservoir through which air is delivered downwardly onto the surface of the liquid; or I may use a tube or tubes of different lengths which in effect merely extend the opening downwardly toward the surface of the liquid.

Referring particularly to Figs. 1 to 5, I will first explain one form of my heater, whence the other forms will be readily intelligible with short explanations of their different variations from the form first explained. In Fig. 1 I have designated the receptacle or reservoir by the numeral 20, the air inlet or inlets by the numeral 22 and the combustion outlet by the numeral 21. In this form the air inlet devices are formed by a series of openings 23 in the upper portion or cover 24 of the receptacle. I have shown some of the openings 23 as extending only through the cover 24 of the receptacle;

and I have shown other of these openings as being continued downwardly into the receptacle by suitable tubes 25. Tubes 25 are of different lengths; and are preferably 5 symmetrically disposed about the vertical axis of the receptacle. I preferably show the tubes in such relative length that there will always be one or more sets of the openings admitting air to the surface of the fuel 10 26; as the surface falls, the lower discharge ends of the tubes 25 are uncovered and the incoming air is then fed through the longest uncovered tubes directly to the surface of the fuel. This provides for a downwardly 15 direct blast of air delivered directly to the surface of the fuel, thereby promoting combustion of the highest efficiency at the surface of the fuel. The flame and gases of combustion pass upwardly and outwardly 20 through combustion outlet 21. In Fig. 1 I have shown this combustion outlet as being confined within a suitable flue 30. This flue 30 is itself contained within the combustion and draft stack 31. Flue 30 may be 25 provided with suitable perforations or apertures 32. It suffices here to say that the burning gases pass upwardly through the opening 21 and through the flue 30, and thence upwardly through the combustion 30 stack 31 and out through the damper controlled top 33. This damper controlled top is comprised in a suitable apertured cap 34 surmounted by a damper member 35 having similar corresponding apertures which may 35 be turned to either register with the apertures in the cap 34 or to shut off those apertures partially or entirely. The stack 31 may be provided with suitable air inlet openings 36 through which air passes as indicated by 40 the arrows, passing upwardly around the tube 30. These openings 36 I have shown as perforations in the stack; but it will be understood that any sort of opening will suffice. The flame passing through the flue 30 derives 45 air from this air stream through the openings 32 and above the top of the flue; and thus the gases are provided with the air necessary to their complete and efficient combustion. The result is to greatly increase 50 the intensity of the flame by providing air for the complete combustion of any solid particles or unconsumed gases which may be carried upwardly from the liquid fuel below.

55 The relative amount of air introduced to the surface and the delivery of flame and heated gases of combustion are regulated by varying the size of the air inlet openings and of the combustion openings at the top 60 of the stack 31. The air inlet openings may be controlled in any suitable manner, and I have typically shown two possible forms in Figs. 4 and 5. In Fig. 4 I have shown the detail of one of the openings 23 coverable 65 by a suitable damper cover 40 pivoted

at 41 to the top or cover 24 of the receptacle. This means provides for regulating the inflow of air to the liquid fuel within the receptacle. In Fig. 5 I have shown another form of damper consisting of a suitable 70 cover cap 42 mounted on supports 43 which may fit into the tube 25 and allow the cover cap 42 to be moved vertically to increase or decrease the area of the opening 44. The cap 42 also has the advantage of covering 75 the opening and protecting it against rain. (It will be understood that the heaters are usually left in the orchard throughout the cold season, ready for constant use as soon as a "cold snap" may proclaim its coming). 80

In this form of heater it is only necessary to ignite the fuel and then to effect suitable regulation of the air supply and combustion outlet. After these are regulated, the flame will emerge from the outlet in suitable volume, consuming all the fuel values. The size and intensity of the flame and combustion may be regulated by suitably regulating the amount of air admitted and the amount of flame allowed to discharge. The relative 85 dimensions of the various parts of the heater may be greatly varied, depending upon the capacities desired and upon the quality of fuel to be consumed, and also upon the rate at which it is desired to consume the fuel. 90 By increasing the height of the combustion stack 31 it is possible to obtain a greatly increased draft which will in turn draw into the apparatus a greatly increased amount of air and accelerate the combustion of fuel. 100

A feature of which I may make especial mention here is the expansion or taking off of a certain amount of gas from the oil within the combustion tube by a certain amount of air. A given amount of air will release 105 and expand from the heated oil and carry a larger amount of gas than the air can efficiently consume. This air, having carried and expanded a certain amount of gas, is reinforced by auxiliary air fed in through 110 the auxiliary air openings hereinbefore described, which openings are adjustable so that they may be used totally or partially, or totally dispensed with, so that the flame handles the fuel in a practical manner to 115 consume any grade of liquid fuel satisfactorily and without producing a large amount of oily soot.

I have shown in Figs. 6 and 7 a form in which the air inlets 36 are controlled by a 120 damper or shutter 40^b with holes 36^a adapted to register with the apertures 36. The admission of auxiliary air may be thus controlled. The air inlet openings 23 may be controlled as shown in Figs. 3 or 5; or they 125 may be controlled by a damper 40^a having holes 23^a to register with the openings 23. The damper 40^a may be connected to the damper 40^b. In any case the flow of air to the fuel through the inlet openings 23 may 130

be regulated so that any desired amount of gas is picked up from the fuel and carried into the combustion stack; while the amount of auxiliary air may be regulated to produce efficient and complete combustion of the gases.

I claim—

1. In an orchard heater, a substantially closed fuel receptacle, means for controllably admitting air into said receptacle to the fuel therein, a short outlet flue extending upwardly from the receptacle, and a combustion stack surrounding the flue of greater height than the flue and of substantially 10 greater diameter than the flue above the upper end of the flue, said combustion stack having no communication with the fuel receptacle other than through the flue, and means to admit air to the lower part of the 15 combustion stack around the flue.

2. In an orchard heater, a substantially closed fuel receptacle, means for admitting air into said receptacle to the fuel therein, a short outlet flue extending upwardly from 20 the receptacle, and a combustion stack surrounding the flue of greater height than the flue and of substantially greater diameter than the flue above the upper end of the flue, said combustion stack having no communication 25 with the fuel receptacle other than through the flue, and means to controllably admit air to the lower part of the combustion stack around the flue.

3. In an orchard heater, a substantially closed fuel receptacle, means for admitting air to the fuel within the receptacle, a short outlet flue extending upwardly from the receptacle, a stack of larger diameter than the flue surrounding the same and projecting 30 some distance above its top, so that a considerably larger combustion space is provided in the stack above the flue rather than in the flue, means for admitting air to the lower part of the stack around the flue to effect 35 complete combustion of the gases emerging from the flue, means for controlling admission of air to the fuel in the receptacle, and

means for controlling admission of air to the stack.

4. In an orchard heater, a substantially closed fuel receptacle, means for controllably admitting air to the fuel within the receptacle, a combustion stack extending upwardly from the fuel receptacle, means to direct combustible gases from the fuel in 50 the receptacle upwardly into the central portion of said stack, and means coöperating with said first mentioned air admission means for controllably admitting air to the lower peripheral portions of the stack. 60

5. In an orchard heater, a substantially closed fuel receptacle, means for controllably admitting air to the fuel within the receptacle, a combustion stack extending upwardly from the fuel receptacle, a flue extending upwardly within the lower portion of the stack having its lower end open to the interior of the fuel receptacle and its upper end discharging into the stack, and means coöperating with said first mentioned air admission means for controllably admitting air to the lower part of said stack around the flue. 70

6. In an orchard heater, the combination of a fuel receptacle having a cover, said 75 cover having a short stack extending upwardly therefrom and opening into the receptacle, an outside stack on the cover spaced from the inner stack and of substantially greater length and of substantially greater 80 diameter above the inner stack than the inner stack, said outer stack having perforations circumferentially around the inner stack, and means for controllably admitting a down-draft of air through a conduit carried by the cover and into the receptacle and 85 over the surface of the oil.

In witness that I claim the foregoing I have hereunto subscribed my name this 30th day of August 1912.

EMANUEL W. DUNN.
